UNITED STATES PATENT OFFICE.

DON R. WESTLAKE, OF ARLINGTON, NEW JERSEY.

SHOESTRING-RETAINER.

1,335,471.

Specification of Letters Patent. Patented Mar. 30, 1920.

Application filed June 24, 1919. Serial No. 306,281.

To all whom it may concern:

Be it known that I, DON R. WESTLAKE, a citizen of the United States, residing at Arlington, in the county of Hudson and

5 State of New Jersey, have invented a new and useful Shoestring-Retainer, of which the following is a specification.

This invention relates to improvements in shoe string retainers, the object of the invention being to provide a device of this 10 character which is simple in construction, economical to manufacture and highly efficient in use.

With the foregoing and other objects in 15 view, which will appear as the description proceeds, the invention consists in the novel features of construction and combination of parts which will be more fully described hereinafter and particularly pointed out in 20 the claims.

In the drawings accompanying and forming part of this specification,

Figure 1 is a perspective view on an enlarged scale, partly broken away, of the 25 device forming the subject-matter of the present invention;

Fig. 2 is a longitudinal section thereof, taken on the line 2—2 of Fig. 1;

Fig. 3 is a cross section taken on the line 30 3—3 of Fig. 1;

Fig. 4 is a fragmentary view of the top of a shoe illustrating the manner of using the improved device; and

Figs. 5 and 6 are plan views of the blanks 35 from which the device is made.

The same characters of reference designate the same parts in the different figures of the drawings.

The device shown herein consists of a pair 40 of members, the blanks from which such members are formed being shown respectively in Figs. 5 and 6. Referring first to Fig. 5, this member consists of a body portion 2 having a plurality of prongs 3 projecting radially therefrom, and which prongs are adapted to be bent at right angles to the body portion and to pierce the material of the shoe top and be bent over toward each other at the inside of such 45 material, thereby to securely retain the device on the shoe. An additional pair of prongs 4 are formed on the blank and are considerably longer than the prongs 3 and carry a curved portion 5 extending rearwardly therefrom. The prongs 4 are first bent up from the member 2 at right angles 50

thereto in the opposite direction from the prongs 3, approximately on the dotted line 7, and then bent downwardly, or in the same direction as the prongs 3, approximately on the dotted line 6, whereby the portions 5 form upstanding ears at opposite sides of the member 2. The blank shown in Fig. 6 is formed of spring steel and has a pair of approximately disk-shaped portions 8 connected together by a straight blank 9. The shank is bowed so that the disks 8 are brought into substantial parallelism with each other.

The device is assembled by placing the 70 disks 8 one above and one below the member 2 and bending the blank to afford a bowed spring, as shown in Figs. 1 and 2, which lies between the ears 5 of the member 2. The upper disk 8 and the member 2 75 preferably pressed or bulged upward and punched up in any suitable manner to form gripping surfaces, as shown in Figs. 1 to 3, to prevent slipping of the shoe string between them. The device is attached to the 80 shoe top approximately in the position shown in Fig. 4, the prongs 3 and 4 being forced through the material of the top and bent over in the manner hereinbefore described so as to securely fasten the device 85 to the shoe. The shoe string, after being laced up to the last hook or eyelet, is folded into a bow and passed downward between the member 2 and the upper disk 8, as shown in Fig. 4. The spring pressure exerted by 90 the disk 8 will positively retain the string against withdrawal. For releasing the string it is only necessary to take hold of the bow or loop thereof and give it a sudden jerk upward.

While I have described in detail the structure herein illustrated, it is to be understood that I do not thereby limit my invention to the precise features of construction shown, as I am aware that many mechanical 100 changes and modifications may be made therein without departing from the spirit and scope of the claims hereto appended.

Having thus described my invention, what I claim is:

1. A device of the class described, comprising a pair of members, one having a plurality of prongs at right angles thereto and adapted to be forced through the material of a shoe top and turned over thereby 110 to secure said member on the shoe, and the other a spring member bent upon itself and

having a portion thereof adapted to lie between said prongs whereby said portion is clamped between the first member and the shoe top, and a portion adapted to overlie said first member and forming therewith a shoe string clamping means.

2. A device of the class described, comprising a pair of members, one having a plurality of prongs adapted to be forced 10 through the material of a shoe top and turned over thereby to secure said member on the shoe, and a pair of upstanding ears, the other member being a spring member having a pair of disk portions connected together by a straight portion, said straight portion being adapted to be bent upon itself 15

to bring said disk portions in substantial parallelism, one of said disk portions being adapted to be clamped between the first member and the shoe top and the other disk portion adapted to overlie said first member and forming therewith a shoe string clamping means, the straight portion of said second member forming a loop between said upstanding ears. 20

25

In testimony that I claim the foregoing as my own, I have hereto affixed my signature in the presence of two witnesses.

DON R. WESTLAKE.
